INVENTOR

UNITED STATES PATENT OFFICE.

NORIC KOMORI, OF NEW YORK, ASSIGNOR TO THE ALEX. SMITH & SONS
CARPET COMPANY, OF YONKERS, NEW YORK.

DESIGN FOR A CARPET.

SPECIFICATION forming part of Design No. 20,263, dated November 4, 1890.

Application filed October 10, 1890. Serial No. 367,644. Term of patent 3½ years.

To all whom it may concern:

Be it known that I, NORIC KOMORI, a subject of the Emperor of Japan, and residing at New York city, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of the body A and the border B. The body A is composed of large conventionalized flower forms surrounded by and connected with large ornamental leaf

scrolls. The border B is composed of an inner margin of scroll forms, a central portion having large conventionalized flower forms surrounded by large leaf-scrolls and an outer margin of irregular figures on shaded ground-work.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.

NORIC KOMORI.
